FOLDABLE METAL AWNING

Nicholas L. Etten, Cedar Falls, Iowa

Application July 11, 1951, Serial No. 236,260

13 Claims. (Cl. 160—58)

1

This invention relates to a foldable metal awning and more particularly to a strong durable metal awning operable between a compact folded position and an extended position and improved operating means therefor.

Conventional foldable awnings such as those constructed of canvas and the like are generally quite flimsy, are susceptible to damage by high winds, wear out quickly, and are generally not attractive in appearance, particularly in retracted position.

An object of the present invention is to provide an improved foldable metal awning which is very strong and very durable.

Another object of the present invention is to provide an improved foldable metal awning which can be readily and smoothly operated between a retracted folded position and an extended position.

A further object of this invention is to provide an improved operating mechanism for retracting and extending a foldable awning.

Still another object of this invention is to provide an awning having improved ventilating structure.

A feature of this invention is in the provision of an awning having a foldable top, extensible side panels being connected to the foldable top, being operated therewith and offering support therefor in the extended position of the awning.

Another feature of this invention is in the provision of an improved rack and pinion operating mechanism for a foldable awning.

Other features, objects and advantages of the present invention will become more fully apparent from the following detailed description taken in conjunction with the accompanying drawings which illustrate a preferred embodiment of the invention and in which:

Figure 1 is a perspective view of an awning constructed according to this invention mounted on a window frame and in an extended position;

Figure 2 is a perspective view of the awning of Figure 1 in retracted or folded position;

Figure 3 is a side elevational view of the awning of Figure 1 in a partially retracted position;

Figure 4 is a broken view, on an enlarged scale, looking downwardly and inwardly on a portion of the awning of Figure 1, certain parts being broken away for clarity of illustration;

Figure 5 is a sectional view, on an enlarged scale, taken substantially along line V—V of Figure 1;

Figure 6 is an enlarged sectional view taken substantially on line VI—VI of Figure 4;

2

Figure 7 is an enlarged fragmentary sectional view taken substantially along line VII—VII of Figure 1;

Figure 8 is an enlarged fragmentary sectional view taken substantially along line VIII—VIII of Figure 1;

Figure 9 is an enlarged fragmentary sectional view taken substantially along line IX—IX in the lower right-hand portion of Figure 5; and

Figure 10 is an enlarged fragmentary sectional view taken substantially along line X—X in the lower left-hand portion of Figure 5.

In general, an awning constructed according to this invention may include an upper louvered top panel or canopy section 20 arranged to be affixed to and extend outwardly from a wall or upper portion of a window or door frame. A pair of fixed side panels 21 and 22 are secured at their upper edge portions to the top panel 20 and are affixed at their inner edges to the wall or side members of the window or door frame.

An intermediate louvered top panel section 23 is hinged at its normally upper edge to the lower edge of the upper fixed top panel 20 and a lower louvered top panel section 24 is hinged at its normally upper edge to the normally lower edge of the intermediate top panel section 23.

A pair of triangulate intermediate side panels 25 and 26 are pivoted adjacent the lower vertex portions thereof to the fixed side panels 21 and 22, respectively, and a pair of outer triangulate side panels 27 and 28 are also pivoted adjacent lower vertex portions thereof to the fixed side panels 21 and 22, respectively, the side panels 25, 26, 27 and 28 all being pivotal on a common axis. The outer louvered top paneled section 24 is hinged to the lower pivoted side panels 27 and 28 for concurrent actuation of both the side panels and the top panels.

With the construction thus far described, movement of the side panels 27 and 28 inwardly will move the parts of the awning between the extended position illustrated in Figure 1 and a compact folded position illustrated in Figure 2. The movement of the louvered top panel sections 23 and 24 and the movement of the pivoted triangulate side panel sections 25, 26, 27 and 28 will be clear from reference to Figures 3 and 4 which show the parts in partially retracted positions.

It will be noted that the movable side panels provide support for the movable louvered top panel sections when the parts are in the extended positions and that the side panels afford protection from rain, snow, sun and the like,

coming from either side. It may also be noted that the same side of the louvered top panel section 24 always faces up so that the awning presents an attractive appearance whether folded or extended.

According to this invention, compact, easily operated and dependable means are provided for moving the parts of the awning between the retracted and extended positions thereof. Referring to Figures 3, 4, 5 and 6, a pair of bell-crank lever arms 31 are each connected to the lower louvered top panel section 24 through a link 32. Referring to Figure 3, it will be seen that clockwise rotation of the levers 31 will move the parts of the awning from the extended to the retracted position.

To actuate the bell-crank levers 31, a rack assembly generally designated by reference numeral 33 is pivotally connected to each bell-crank lever 31. A pinion 34 meshes with each of the rack assemblies 33 and both pinions 34 are connected to a double-pulley assembly generally designated by reference numeral 35. Portions of a rope 36 are wound in opposite directions on the sections of the double-pulley 35 so that the pulley may be rotated in either direction to retract or extend the movable parts of the awning.

Having described the general make-up and operation of the operating mechanism, the component parts of the mechanism will now be described. The bell-crank lever 31 is formed from two triangulate plates 38 and 39 which are formed with central inwardly oppositely recessed portions 38a and 39a, respectively, which are disposed in abutting relation and secured together by rivets 40, the aligned outer edges of the plates 38 and 39 thereby being in spaced relationship.

The link 32 has a generally U-shaped cross section and one end of the link extends between the plates 38 and 39, a bolt 41 extending through the plates 38 and 39 and the link 32 to afford a pivotal connection between the lever 31 and the link 32. The other end of each link 32 is connected to the lower louvered top panel section 24 through a unique arrangement which holds this top panel section in locked position when extended and which releases the top panel section from the locked position when the operating mechanism is actuated for folding the awning. This arrangement will be described in detail hereinafter.

Both levers 31 are pivoted on a tie-bar 43 which is affixed between the fixed side panels 21 and 22. To secure the tie-bar 43 to the side panels 21 and 22, a pair of brackets 44 and 45 are mounted on the fixed side panels 21 and 22, respectively, the brackets 44 and 45 having inwardly projecting portions 44a and 45a, respectively, into which the ends of the tie-bar 43 extends.

The brackets 44 and 45 also have inwardly projecting portions 44b and 45b, respectively, which are machined to provide internal shaft-receiving bearing surfaces. Each pinion 34 has an integral shaft portion 34a journaled in one of the bearing portions 44b and 45b. Each pinion 34 also has an integral shaft portion 34b secured into one end of a connecting hollow shaft 46. Thus rotation of the shaft 46 will rotate both of the pinions 34.

Each rack assembly 33 includes a pair of spaced generally L-shaped plates 47 between which a toothed rack 48 is disposed, rivets 49 extending through the plates 47 and the rack 48 to secure them in assembly. Each plate 47 has an elongated slot 47a (Figure 6) through which the shaft 70

34a of the pinion 34 extends to maintain the teeth of the pinion in mesh with the teeth of the rack. The plates 47 of each rack assembly 33 have portions 47' which extend between the spaced outer edge portions of the plates 38 and 39 forming the bell-crank lever 31, as seen in Figures 3, 4 and 5, the pivotal connection between the rack assembly 33 and the bell-crank lever 31 being provided by a pin 50 extending through terminal end parts of the portions 47' of the plates 47 and through the plates 38 and 39. It will thus be seen that rotation of the pinions 34 clockwise, Figure 6, will move the rack assembly 33 inwardly and upwardly to pivot the bell-crank lever 31 clockwise about the tie-bar 43 and thus retract and fold the movable parts of the awning.

The double-pulley 35 is constructed from a pair of outer circular plates or disks 51 and a center plate or disk 52. The outer circular plates 51 are formed with central inwardly recessed portions 51a which abut the center disk 52, the three disks being secured together by rivets or the like extending through the recessed portions 51a and the center disk 52. The center disk 52 may be affixed to the hollow shaft 46 in any desired manner.

A portion 36a of the rope 36 is wound clockwise (as viewed in Figure 5) around the right-hand portion of double-pulley (as viewed in Figure 4) while a portion 36b of the rope 36 is wound in an opposite direction around the other portion of the double-pulley. Thus a downward pull on portion 36a will rotate the pulley and pinion 34 clockwise, while a downward pull on portion 36b will rotate the pulley and pinion counter-clockwise. As shown in Figure 2, the looped end of the rope 36 may be wound around or tied to a cleat 53 mounted on one side member of the window or door frame so that the actuating mechanism for the awning may be held in any desired position.

A rope guide is provided adjacent the pulley 35. This guide includes a generally arcuate plate 54 disposed in proximity to the periphery of the pulley 35, the plate 54 having a pair of guide openings through which the portions 36a and 36b of the rope 36 extend. The plate 54 is formed with a terminal hook-like end extending around the tie-bar 43. A generally U-shaped support member 55 is secured to the plate 54 and has portions extending on either side of the pulley 35 and pivoted on the shaft 46.

According to this invention, the louvered top panel sections and the side panel sections are constructed and assembled in a novel manner such that they are readily fabricated and assembled, durable, and efficient, quiet and reliable in operation.

As seen in Figures 4 and 5, the upper fixed top panel section 20 includes a pair of angularly formed side channels 57 and 58 which have integral upper terminal attachment ears 57a and 58a, respectively. An upper sheet metal louver 59 abuts against the lower surface of the upper legs or flanges of the side panels 57 and 58 and is formed with an upturned flange abutting the attachment ears 57a and 58a. A rigidifying bar 60 having a generally L-shaped cross-section abuts the lower surface of the louver 59 and inward surface of the upturned flange thereof. Rivets 61, or the like, secure the louver 59 and bar 60 to the side channels 57 and 58. The louver 59 and the bar 60 preferably have inverted keyhole openings therein aligned with like openings in the ears 57a and 58a for attach-

ment to the window or door frame by screws or the like.

For attachment to the fixed side panels 21 and 22, the side channels 57 and 58 are formed with downturned flanges 57b and 58b, the upper edge portions of the side panels 21 and 22 being secured to the flanges 57b and 58b, respectively, by rivets or the like. The side channels 57 and 58 and the upper louver 59 may be additionally tied together by a pair of brackets 62 secured to the flanges 57b and 58b and to the upper louver 59.

A plurality of louvers 63, four being illustrated in the drawings, may be secured between the side channels 57 and 58. For this purpose, a pair of louver support brackets 65 and 66 are secured to the downturned flanges 57b and 58b, respectively, of the side channels. The brackets 65 and 66 are formed with spaced integral stepped portions 65a and 66a to which the louvers 63 are secured, rearward portions of the louvers 63 abutting associated stepped portions 65a and 66a and being secured thereto by rivets while forward portions of the louvers are secured to associated stepped portions 65a and 66a through spacers 67. The rearward edge of each louver 63 is upturned while the forward edge portion is downturned so that rain, snow and the like will be effectively excluded while ventilation air may readily flow between the louvers.

The intermediate louvered top panel section 23 has a construction somewhat similar to that of the fixed top panel section 20 and includes a pair of side channels 69 and 70 between which a plurality of louvers 71 are secured. For this purpose, the lower legs or flanges of the side channels 69 and 70 are formed with integral spaced stepped portions 69a and 70a, respectively. As shown in Figure 5, rearward portions of each of the louvers 71, except the rearward louver, abut associated step portions 69a and 70a and are secured thereto by rivets. Forward portions of each of the louvers 71, except the forward louver, are secured to associated step portions 69a and 70a through spacers 72. Rearward portions of the rearward louver 71 are secured to the channels 69 and 70 through bracket plates 73 riveted to the louver and to the side channels. Forward portions of the forward louver 71 are secured to the side channels 69 and 70 through bracket plates 74 riveted to the louver and to the side channels.

To hinge the top panel section 23 to the affixed top panel section 20, the side channels 57 and 58 of the fixed top panel 20 are formed with integral looped portions 57c and 58c, respectively, and the side channels 69 and 70 of the top panel sections 23 are formed with integral looped portions 69b and 70b, respectively, hinge pins 75 extending through associated aligned looped portions 57c and 69b and associated aligned looped portions 58c and 70b.

The lower top panel section 24 includes a main portion aligned with the top panel sections 23 and 20 in the extended position thereof and a lower valance portion downturned with respect to the main portion. A pair of side members 77 and 78 have cross-sections of generally channel shape opposite the main portion and L-shaped cross-sections opposite the valance portion. A plurality of louvers 79, three being illustrated, are supported between the side members 77 and 78. For this purpose, the lower legs or flanges of the channel-shaped portions of the side members 77 and 78 are formed with stepped portions, rearward portions of the louvers 79 be-

ing riveted to associated stepped portions and forward portions of the louvers 79 being secured to associated stepped portions through spacers 80, in substantially the same manner as above described.

Each louver 79 has an upturned rearward edge portion and a downturned forward edge portion, the louvers being disposed in overlapping relation so that rain, snow and the like are effectively excluded while ventilation air may flow freely between the louvers.

Looking now at Figures 5 and 9, it will be seen that a valance plate 81 extends between the side members 77 and 78 and is secured in abutting relation to the inwardly extending legs or flanges of the valance portions of members 77 and 78 and in abutting relation to the inward surface of the downturned forward flange of the forward louver 79. For additional support of the valance plate and for rigidifying the structure, integral tabs may extend from the lower flange of the channel-shaped portions of side members 77 and 78, the tabs being riveted to the valance plate 81. For further rigidity, the valance plate 81 preferably has a lower inturned flange portion 81a and, for still further rigidity and to support hinge structures to be described, a valance channel 82 extends between the valance portions of the side members 77 and 78, the channel being riveted or otherwise secured to the valance plate 81 and flange portion 81a thereof and having integral tabs or ears 82a riveted to the associated portions of the side members 77 and 78.

To hinge the section 24 to the section 23, the side channels 69 of the section 23 and the side member 77 of the section 24 are formed with integral aligned hinge loops and the side channel 70 of the section 23 and the side member 78 of the section 24 are also formed with integral aligned hinge loops, hinge pins 83 extending through the associated hinge loops, Figures 4 and 5.

According to this invention, novel and highly advantageous structures, illustrated best in Figures 5 and 9, are provided for hinging the top panel sections 24 to the side panels 27 and 28 and for connecting the links 32 to the top panel sections 24.

Each of the side panels 27 and 28 has a hinge loop 85 extending from the outer lower corner thereof. A pair of straps 86 forming spaced aligned hinge loops are disposed on either side of each loop 85 and welded or otherwise secured to the valance channel 82. A hinge bracket 87 has spaced aligned hinge loops or bearing portions 87a aligned on either side of each loop 85 and between the loops 86. A hinge pin 88 extends through the associated loops 85, 86 and 87a so that each of the side panels 27 and 28 is pivotally hinged to the top panel section 24, each bracket 87 being pivotally movable on the associated hinge pin 88.

Each bracket 87 has an arm portion 87b pivotally connected to one end of the associated link 32. For this purpose, a pin 90 extends through the spaced legs or flanges of each channel-shaped link 32 and through an opening in the end of the associated arm portion 87b. Each bracket 87 also has a portion 87c resiliently urged into engagement with the channel 82. A pair of bolts 91 extend through the channel 82 and through the portion 87c of each bracket, a helical compression spring 92 is disposed on each bolt 91, and a cotter pin 93 is disposed on each

bolt to hold the associated spring 92 thereon so that the portion 87c of each bracket 87 is resiliently urged toward the channel 82.

With this arrangement, the movable top sections 23 and 24 may be resiliently locked in extended position. It will be seen that when the parts are in the position illustrated in Figure 3, for example, each compression spring 92 will hold the associated portion 87c in engagement with the channel 82. When the bell-crank levers 31 are actuated to pivot in a counterclockwise direction (Figures 3 and 5) the portion 87c will remain engaged with the channel 82 until the top sections and side panels are substantially in the positions illustrated in Figure 5. Further counterclockwise rotation of bell-crank levers 31 will rotate only the brackets 87 counterclockwise against the action of compression springs 92. The levers 31 are preferably rotated to over-center positions, that is, with the axes of pins 41 upwardly spaced from a line through the axes of the tie-rod 43 and pin 90 as illustrated in Figure 5. The compression spring 92 will then resiliently maintain the top panel sections, bell-crank levers 31 and links 32 in the positions illustrated in Figure 5.

To fold the awning, the levers 31 are, of course, rotated clockwise. It will be noted that the axis of pin 90 is well below a line through the axes of hinge pins 75 and 83 in the extended position of Figure 5 so that on-center or over-center locking of the top panel sections 23 and 24 cannot occur. Thus the top panel sections are resiliently locked in the extended position through the co-operation of compression spring 92, bracket 87, links 32 and levers 31, but may be readily folded by actuation of the levers 31.

Referring to Figures 5 and 7, it will be seen that each of the fixed side panels 21 and 22 is preferably formed with inturned flanges at the inner and outer edges thereof to rigidify the same. The flanges at the inner edges of the fixed side panels are preferably secured to the window or door frame as by screws. Strips 95 of wood or the like may be affixed to each of the fixed side panels 21 and 22 adjacent the outer edges thereof to deaden the same against vibrations.

The movable panels 25, 26, 27 and 28 may be similarly formed with inturned rigidifying flanges at each edge thereof. Adjacent the outer edge of each of the side panels 25 and 26 a wood strip 96 is secured to deaden each panel against vibrations. Adjacent the outer edge of each of the side panels 27 and 28 a rigidifying channel 97 is secured as by riveting. The hinge loops or bearings 85 described above and shown in Figure 9 are preferably formed as integral parts of the channels 97.

Referring to Figures 5 and 10, I have shown the pivotal connections between the movable side panels and fixed side panels as each including a bracket 98 formed with a pair of spaced parallel arms, each bracket 98 being secured to the inside lower edge portion of the associated fixed side panel. A pivot pin 99 extends through a fixed side panel and to the arms of the associated bracket 98, and each movable triangulate side panel is pivoted adjacent a lower vertex portion thereof on the associated pin 99. In order to maintain the side panels in spaced relation on the pin 99, each of the fixed side panels has an integral portion 100 extending inwardly, each movable side panel is provided with an outwardly deformed portion adjacent the pivot pin 99 and a washer 101 is disposed on the pin 99 between

each pair of movable side panels. For additional pivotal support of each of the movable side panels 27 and 28, a bifurcated hinge bracket 102 is riveted or otherwise secured to the end portion of the associated rigidifying channel 97, each pin 99 extending through the arms of the associated hinge brackets 102.

To guide each of the movable side panels 25 and 26 in its pivotal movement, an arcuate arm 103 is pivoted at one end on the associated fixed side panel by means of a rivet 104, Figures 5 and 7. The other end of each arcuate arm 103 has a transverse slot therein through which a bolt 105 affixed to the associated fixed side panel extends. A tension spring 106 connects the inner end of each arm 103 to the associated side panels and resiliently urges the arm upwardly. A headed pin 107 is affixed to each of the movable side panels 25 and 26 and engages the upper edge of the associated arm 103 to guide the side panel in its pivotal movement. It will be readily seen that the tension spring 106 will maintain each arm 103 and associated pin 107 in operative engagement.

A spring-urged arm may be provided on each of the side panels 25 and 26 to guide the associated one of the side panels 27 and 28 in its pivotal movement, or, as illustrated in Figures 5 and 8, a plate 108 may be affixed to each of the panels 25 and 26, each plate being formed with an upper edge inwardly spaced from the inner surface of the associated side panel and having an arcuate upper edge such that all points on the upper edge are substantially equidistance from the axis of the pivot pins 99. A headed pin 109 is affixed to each of the side panels 27 and 28 and engages the upper edge of the associated plate 108 to guide the panels 27 and 28 in their pivotal movement with respect to the side panels 25 and 26.

In summary, a highly advantageous foldable metal awning is provided by this invention which is strong, resistant to the elements in both folded and extended positions, durable, attractive in appearance, easily, smoothly and quietly operable, and readily and economically manufacturable.

It will be apparent that modifications and variations may be effected without departing from the spirit and scope of the novel concepts of the present invention.

I claim as my invention:

1. An awning comprising a foldable top, a lever linked to said top for operating the same between retracted and extended positions, and rope and pulley operated rack and pinion means connected to said lever for actuating the same.
2. An awning comprising a foldable top, a lever, and means connecting said lever to said foldable top, said lever being swingable to actuate said top between retracted and extended positions, and said connecting means including spring means resiliently locking the top in extended position.
3. An awning comprising a foldable top, a rack assembly connected to said foldable top for actuating the same between retracted and extended position, and including a toothed rack, and a toothed actuating pinion rotatable in the awning, said rack assembly including means guiding said rack to maintain the teeth of the rack and the teeth of the pinion in meshing relation.
4. An awning comprising a plurality of top panel sections hingedly connected, a lever linked to one of said top panel sections for actuating said sections between extended positions and compact, folded positions, and rope and pulley

operated rack and pinion means connected to the lever for actuating the same.

5. An awning comprising a plurality or hingedly connected top panels, a lever, a bracket hinged to one of said top panel sections and having a pair of arm portions, a link pivotally connected at one end to said lever and at the other end to one of said arm portions and said one top panel section, said lever being rotatable to actuate the top panel sections between folded and extended positions, and spring means acting to resiliently lock the top panels in extended position.

6. An awning comprising a foldable top, rack and pinion means for operating the top between folded and extended positions, and means for actuating the rack and pinion means including a double-sectioned pulley, a first rope portion wound in one direction around one section of the pulley, and a second rope portion wound in a reverse direction around the other section of the pulley, whereby the rope portions may be selectively actuated to operate the awning into retracted or extended positions.

7. In an awning having a foldable top and a pair of sides each including a plurality of pivoted side panels, the top and sides being connected for concurrent actuation between retracted positions in which the top is compactly folded and the side panels of each side are disposed in nested relation and extended positions in which the top is extended and the side panels abut and support the top, a lever, and means connecting said lever to the foldable top, said lever being rotatable to retract and extend the awning, and said connecting means including spring means for resiliently locking the awning in extended position.

8. An awning comprising a plurality of hingedly connected top panels, a lever below said top panels, a bracket hinged to one of said top panels and having an inwardly extending arm portion connected to said lever, spring means between said bracket and said one top panel for urging said arm portion downwardly, said lever being rotatable to actuate said top panels between compact folded positions and extended positions, said spring means cooperating with the lever and bracket to lock the panels in extended positions.

9. An awning comprising a foldable top and foldable sides connected thereto, a double-section

5 pulley connected to the foldable sides and top and rotatable in one direction to extend the top and sides and in a reverse direction to retract the top and sides, a first rope portion wound in one direction around one section of said pulley, and a second rope portion wound in a reverse direction around the other section of said pulley, said rope portions thereby being selectively actuatable to retract or extend the awning.

10 10. A foldable awning, comprising a canopy of hinged sections movable into superposed relationship when folded, a pair of sides each including sections movable into juxtaposed relationship when folded, rack and pinion means, linkages connected to the rack means and to a movable part of said awning, and means to actuate the pinion means in either direction to fold and extend the awning.

15 11. A foldable awning comprising a canopy including a fixed section, a first movable section 20 hinged to said fixed section and a second movable section hinged to said first movable section, and a lever and link assembly connected between said fixed section and said second movable section and actuatable for folding and extending said canopy.

25 12. An awning comprising a foldable canopy, and a pair of sides each including a fixed panel, an intermediate pivotal panel and an outer panel, said intermediate and outer panels being foldable 30 into juxtaposed relationship with said fixed panel and extensible into supporting relationship with said canopy, said intermediate side panels being free from direct connection to said foldable canopy, and said outer side panels being connected to said foldable canopy for concurrent actuation therewith.

35 13. In a foldable awning, folding and extending means comprising a lever, and a link connected between said lever and said awning, said lever and link being movable into over-center relationship to hold said awning rigidly extended.
